(57) **CLAIM**

The ornamental design for a LED lamp, as shown and described.

DESCRIPTION

FIG. 1 is a perspective view of the front left side of an LED lamp;

FIG. 2 is a plan view of the front of the LED lamp of FIG. 1;
FIG. 3 is a plan view of the left side of the LED lamp of FIG. 1;

FIG. 4 is a plan view of the right side of the LED lamp of FIG. 1;

FIG. 5 is a plan view of the top of the LED lamp of FIG. 1;
FIG. 6 is a plan view of the back of the LED lamp of FIG. 1;
and,

FIG. 7 is a plan view of the bottom of the LED lamp of FIG. 1.

The broken lines are for illustrative purposes only, and their presence and position form no part of the claimed design.
